UNITED STATES PATENT OFFICE.

EMIL F. LEWIS FRITZ, OF CHICAGO, ILLINOIS.

LOADING DEVICE.

Application filed September 30, 1922. Serial No. 591,625.

My invention relates to novel improvements in loading devices, and has for its principal object the provision of an improved construction of this character which will be highly efficient in use and economical in manufacture.

A further object of the invention is the provision of a conveyor capable of being adjusted vertically, one which can be raised or lowered to meet the required height of a hay wagon, or the like in which matter carried by the conveyor is discharged.

Other objects will appear hereinafter.

The invention consists in the combinations and arrangements of parts hereinafter described and claimed.

The invention will be best understood by reference to the accompanying drawings forming a part of this specification, and in which:

Fig. 1 is a longitudinal vertical sectional detail view of a loading device, embodying the invention;

Fig. 2 is a fragmentary vertical sectional detail view of the discharge end of the conveyor embodied in the invention;

Fig. 3 is a fragmentary top plan view, of the same;

Fig. 4 is a fragmentary sectional detail view of one of the lock members embodied in the invention;

Fig. 5 is a sectional detail view taken substantially on line 5—5 of Fig. 1;

Fig. 6 is a sectional detail view of one of the hay gathering fingers embodied in the invention;

Fig. 7 is a sectional detail view taken substantially on line 7—7 of Fig. 1;

Fig. 8 is a sectional detail view taken substantially on line 8—8 of Fig. 7;

Fig. 9 represents a vertical sectional view taken approximately on the line 9—9 of Fig. 7; and

Fig. 10 represents a cross sectional view through the machine taken approximately on the line 10—10 of Fig. 1.

Referring to the drawings, 10 indicates an angular frame carried by wheel bearing axle 11 journaled through suitable bearings 12 and fixed thereto by pins 11'. Carried by frame 10 are suitable bearings 13 through which shaft 14 is journaled, said shaft 14 being provided with sockets 15 for the reception of the upper end portions 16 of rake

members A which are held secured to the shaft 14 within the sockets 15 through the medium of suitable set screws 17.

Each of the rake members A are formed, in the present instance, in two parts, the lower part being indicated at 18 and provided with a socket 19 for the reception of the end portion of the upper part 16 of each of the rake members, the said parts of each of said rake members being rigidly held together through the medium of a set screw 20 as shown in Fig. 4. By this arrangement should either part of any one of the rake members become damaged, the damaged part can be readily detached and a new part substituted therefor.

In the present instance the rake members A are capable of being adjusted relatively with respect to the matter or ground over which they pass and this is accomplished through the medium of adjusting levers 21 carried at the opposite ends of the shaft 14 and provided with lock mechanism 22 arranged and adapted to engage ratchet segments 23 as illustrated in Fig. 1. By this construction it will be obvious that by movement of the levers 21 the rake members can be raised or lowered into or out of engagement with the ground or matter to be gathered and that the rake members can be raised sufficiently far enough above the ground to an inoperative position when the loader is not in use.

As matter is gathered by the rake members it is received by a continuous conveyor 24, formed of flexible material, such as canvas or the like, and passing over rollers or drums 25 and 26. The conveyor in this instance is provided on its roller engaging surfaces with narrow equally spaced apart metal strips or wear plates 27 extending longitudinally with respect to the conveyor, the purpose of which is to prevent undue wear on the conveyor; rollers 27' being provided to prevent sagging of the conveyor.

The rollers 25 and 26 are mounted on shafts 28 and 29, the shaft 28 being supported by depending arms 30 carried by the frame 10. The shaft 28 carries inclined side rails 31 preferably, for sake of lightness, formed of wood, and which carry at their upper ends the shaft 29 carrying roller or drum 26, the side rails being free to pivot on the shaft 28 for the purposes to be hereinafter stated.

As alluded to, one of the objects of the in-

vention is to provide means for adjusting the conveyor to meet the required height of a hay wagon, or the like, in which matter is to be deposited and to accomplish this object 5 I support the shaft 29 for turning movement in an angular U-shaped support 32 carrying oppositely disposed pivotally mounted rack plates 33 adapted for engagement with gears 34 carried on shaft 35, as best shown in 10 Fig. 7.

The rack plates 33 are held in engagement with the gears 34 through the medium of U-shaped collars 36 carried on shaft 35 as clearly shown in Figs. 7 and 8. The shaft 35 is 15 journaled in suitable bearings 37 carried by frame 10 and is operated through the medium of a hand crank 38 mounted on each of the opposite ends of the shaft 35. The shaft 35 carries ratch wheels 39 adapted for engagement with pawls 40 carried by frame 10, said pawls being preferably double acting spring controlled pawls which are well known in the art. The purpose of the pawls 40 is to lock the conveyor in its desired 20 adjustable position. It will be obvious from the description that I provide a novel and durable arrangement for raising or lowering the discharge end of the conveyor. The side rails 31 being loosely mounted on the shaft 25 28 permit the vertical pivotal movement of the conveyor.

The conveyor 24 is operated by movement of the wheels 41 carrying frame 10 and which are carried by axle 11; the operative 30 movement of the conveyor being accomplished through the medium of gears 42 meshing with gears 43 carried by the wheels 41 and shaft 28 respectively. The shafts 28 and 29 carry sprocket gears 44 over which 35 sprocket chains 45 pass. By this arrangement motive power is supplied to the conveyor when the device is in motion.

The conveyor 24 carries equally spaced transverse slats 46 each of which carry 40 equally spaced apart fingers 47 as best shown in Fig. 1, said fingers each having their fixed ends provided with a screw threaded stud 48 by means of which the finger is removably fixed to the slats 46. By 45 this arrangement should any one of the fingers become damaged, I am able to remove the damaged finger and substitute a new one therefor, the purpose of the fingers being to force the matter gathered by the 50 rake members onto the conveyor 24.

Figs. 2 and 3 illustrate fragmentary views of the mechanism for removing the matter received by the conveyor. This mechanism comprises a shaft 49 carried by side rails 31 55 and carrying equally spaced apart removable fingers 50 adapted to pass between the fingers 47 in order to remove matter from the conveyor. The shaft 49 carries a gear 51 meshing with an idle gear 52 which 60 in turn meshes with a gear 53 carried by

shaft 29, this arrangement being such that the shaft 49 will rotate in opposite direction of the shaft 29.

The side rails 31 carry a plurality of removable equally spaced apart Z-shaped 70 brackets 53' mounted in sockets 54 carried by the side rails 31. The Z-shaped brackets 53' carry canvas or metal strips 55, the purposes of which are to prevent the wind from blowing matter off of the conveyor during 75 its travel thereon.

As shown in Fig. 1 the frame 10 is provided with means for attaching the loading device to a hay wagon, or the like, said means being in this instance indicated at 80 56 and may be of any approved construction or type.

When the loading device is not in use, I provide at the front end of the frame 10 adjacent the opposite sides thereof adjustable props 57 which are held in the desired 85 adjusted position through the medium of bolts 58 adapted to work in elongated slots 59 formed in the ground engaging end portions of the props. 90

By the provisions of the novel improvements of the invention as herein set forth, it will be obvious that my loading device will prove to be of great value in the agriculture art and can be economically manufactured as well as efficiently operated. 95

While I have illustrated and described the preferred form of construction for carrying my invention into effect, this is capable 100 of variation and modification without departing from the spirit of the invention. I, therefore, do not wish to be limited to the precise details of construction set forth, but desire to avail myself of such variations and modifications as come within the scope of 105 the appended claims.

Having described my invention what I claim as new and desire to secure by Letters Patent, is:

1. In a rake and loader, an elevating device comprising a conveyor; a driving shaft supporting one end of the conveyor and arranged to afford a pivot during the elevating and lowering movements thereof; a U-shaped end frame, on the legs of which the opposite end of the conveyor is pivotally mounted for its support; rack plates depending from the connecting bar of said U-shaped frame; and adjusting shaft having 110 teeth with which the rack plates are engaged for support and adjustment; and means for locking the adjusting shaft in adjusted position, substantially as described.

2. In a rake and loader, a trailer frame 115 having support on travel wheels; a driving shaft operatively supported on said frame; side rails pivoted at their lower ends on said driving shaft and pivotally carrying a top shaft at their upper ends; an endless conveyor operatively arranged upon the 120

driving shaft and top shaft; a **U**-shaped end frame, on and between the legs of which the top shaft is operatively mounted; rack plates depending from the connecting bar of the **U**-shaped frame; an adjusting shaft operatively mounted on the trailer frame and equipped with teeth with which the rack plates are engaged for support and adjustment; means for operating the adjusting shaft; and means for locking the adjusting shaft in adjusted position, substantially as described.

3. In a rake and loader, an elevating

device comprising a conveyor having one end affording a pivot during elevating and lowering movements thereof, a **U**-shaped support pivotally carried at the other end of the conveyor, toothed bars pivotally depending from said **U**-shaped support, a shaft carrying toothed members for meshing with said toothed bars, and means for locking said shaft in adjusted position, substantially as described.

In testimony whereof I have signed my name to this specification.

E. F. LEWIS FRITZ.
